UNITED STATES PATENT OFFICE.

CHARLES W. McGONIGLE, OF ALGONA, WASHINGTON, ASSIGNOR OF ONE-HALF TO
GEORGE E. MILLER, OF PORT ORCHARD, WASHINGTON.

ELECTROMAGNETIC SOUNDING APPARATUS.

1,023,215.

Specification of Letters Patent.

Patented Apr. 16, 1912.

Application filed August 9, 1910. Serial No. 576,337.

To all whom it may concern:

Be it known that I, CHARLES W. McGONIGLE, a citizen of the United States, residing at Algona, in the county of King and State 5 of Washington, have invented a new and useful Electromagnetic Sounding Apparatus, of which the following is a specification.

This invention relates to that class of sounding apparatus in which the sound is 10 produced by a rapidly vibrating metallic diaphragm, the vibrations of the diaphragm being effected by means of an electromagnet.

It is the object of the present invention to provide a device of the kind stated which 15 is compact in form, and simple in construction, and which produces a loud tone.

The invention also has for its object to provide a novel construction and arrangement of parts to be hereinafter described 20 and claimed, and in order that the invention may be better understood, reference is had to the accompanying drawing forming a part of this specification, in which drawing—

25 Figure 1 is a central vertical section of the apparatus. Fig. 2 is a plan view thereof partly broken away.

Referring specifically to the drawing, the 30 casing of the apparatus is in two sections indicated at 5 and 6 respectively, between which is held a resilient metal diaphragm 7. The contiguous ends of the sections 5 and 6 are formed with flanges 8 and 9, respectively, the flange 8 extending outwardly 35 from the section 5, and the flange 9 extending inwardly from the section 6. The diaphragm 7 is received between the flanges, and by means of bolts or other suitable fastening means 10 passing through the flanges, 40 and through the portion of the diaphragm therebetween, the two sections of the casing, as well as the diaphragm, are securely connected together.

45 The casing section 5 is frusto-conical, and the section 6 is flared or bell-shaped. The section 6 is secured to the larger end of the section 5.

50 Mounted within the casing section 5 are two electromagnets 11, the cores 12 of which extend in close proximity to the diaphragm 7, the latter thus forming the armature of the magnets. From one of the magnets extends a post 13 which passes through an opening 14 in the diaphragm, and is formed 55 above the latter, with a lateral extension

through which is threaded a screw 16. To the diaphragm 7 is fastened a flat spring 17, the free end of which is normally in contact with the point of the screw 16. The screw may be provided with a platinum point, and a lock nut 18 is also provided.

To the casing section 5 are connected binding posts 19 and 20, respectively. The binding post 20 is insulated from the wall of the casing section. The binding post 19 is electrically connected to the casing section. From the binding post 20 a conductor wire 21 extends to the magnets. The magnets are connected, and from one of them extends a wire 22 which is connected to the post 13. A battery or other source of electrical energy is indicated at 23, one side of which is connected to the binding post 19, and the other side to the binding post 20. A suitable switch 24 is interposed in one of the conductors leading from the battery.

75 The operation of the apparatus is as follows: Upon closing the electric circuit, the electromagnets 11 are energized and cause the circuit to be made and broken rapidly through the contacts 16 and 17. The circuit is as follows: from one side of the battery 23 to the binding post 20, thence by wire 21 to the magnets, and by wire 22 to the post 13, and thence to the contact screw 16, and as said screw is in contact with the spring 17, the circuit is continued through said spring, and through the diaphragm, and the casing, to the binding post 19, and thence to the other side of the battery. The magnets being energized, draw the diaphragm 7 downwardly, and cause the circuit to be opened between the contact screw 16 and the spring 17. The magnets are thus deenergized, whereupon the diaphragm is released, and it springs back, and again places the spring 17 in contact with the screw 16, thus again closing the circuit, and again energizing the magnets. This operation is repeated in quick succession, and the diaphragm is thus rapidly vibrated, thereby producing a loud sound which is amplified by the bell-shaped section 6 of the casing. It will be noted that the contact screw 16 is not attached to any vibrating portion of the apparatus, and it therefore does not interfere with or diminish the sound production.

100 The apparatus is simple in construction, and compact in form, and it is especially 110

adapted for automobiles, motor boats, electric railways, or any other apparatus requiring an audible signal. A comparatively weak current is required to operate the device, and the very high rate of vibration of the diaphragm produces a shrill note of great carrying power.

5 The casing section 5 is provided with a base 25 for securing the device in place, which may be done by means of bolts or any other suitable fastening means 26.

What is claimed is:

10 A device of the class described comprising a flaring, sound-amplifying element, the inner surface of which is continuous and unbroken; a diaphragm located at the smaller end of the sound-amplifying element; and a means for adjusting the pulsations of the diaphragm, which means is spaced from the 15 sound-amplifying element and supported independently of the vibrating portion of

the diaphragm, said means being located to the front of the diaphragm, within the sound-amplifying element, and being accessible for adjustment through the open end of 25 the sound-amplifying element; the device including also an electromagnet rigidly supported to the rear of the diaphragm; an angular post secured to the magnet and protruding through the diaphragm to overhang the forward face of the diaphragm; the said means consisting of an adjusting screw threaded into the post, in front of the diaphragm.

In testimony that I claim the foregoing 35 as my own, I have hereto affixed my signature in the presence of two witnesses.

CHARLES W. McGONIGLE.
